(57) **CLAIM**

The ornamental design for a grinder, as shown and described.

DESCRIPTION

FIG. 1 shows a perspective view of the grinder showing our new design.

FIG. 2 shows a front, elevation view of the grinder shown in FIG. 1.

FIG. 3 shows a rear, elevation view of the grinder shown in FIG. 1.

FIG. 4 shows a right, elevation view of the grinder shown in FIG. 1.

FIG. 5 shows a left, elevation view of the grinder shown in FIG. 1.

FIG. 6 shows a top, plan view of the grinder shown in FIG. 1.

FIG. 7 shows a bottom, plan view of the grinder shown in FIG. 1; and,

FIG. 8 shows another perspective view of the grinder shown in FIG. 1. In this view the handle of the grinder is shown folded over the mouth of the grinder.

The broken lines in FIGS. 1-8 show portions of the grinder that form no part of the claimed design.

1 Claim, 4 Drawing Sheets
